UNITED STATES PATENT OFFICE.

FRANCIS R. DUCK, OF CHICAGO, ILLINOIS.

MANUFACTURE OF PAPER BOXES.

SPECIFICATION forming part of Letters Patent No. 229,524, dated July 6, 1880.

Application filed July 19, 1878.

To all whom it may concern:

Be it known that I, FRANCIS R. DUCK, of Chicago, Illinois, have invented a certain new and useful Improvement in the Manufacture 5 of Boxes; and I hereby declare that the following is a full, clear, and exact description of the same, reference being had to the accompanying drawings, which form a part of this specification.

10 My said invention relates to that class of boxes generally made of paper and known as "neck" or "flanged" boxes, being constructed in such manner that the flange or rim of the cover when applied to the body of the box will be flush therewith. For this purpose the box-
15 body has a flange at one or both ends, which is of less thickness than the remainder of the body over or within which flange the cover sets, giving a flush surface between the body and cover. As heretofore constructed the tubes or bodies of such boxes have been made of two or more pieces, wrapped one about the other, and fastened together in such relative positions that one piece would extend farther
20 than the other at the end of the finished tube or body, and thus form the flange or extension described thinner than the body, and adapted to receive the flanged cover or bottom, as stated.

25 My improvement consists in making the box tube or body of a single piece or sheet folded and secured upon itself in two or more contiguous layers, which layers, in the finished tube or body, extend unequally at the end thereof, and thus form a flange and shoulder adapted to receive a flanged cover or bottom flush with the surface of said tube or body.

30 This will be more clearly understood by reference to the drawings, in which Figures 1 and 2 represent blanks or sheets of proper form to make my improved box tube or body; and Figs. 3 and 4 represent tubes made, respectively, from said blanks.

35 That is to say, A, Fig. 1, is a sheet of proper form to make the tube or body shown in Fig. 3; and B, Fig. 2, is a sheet of suitable shape to form the tube illustrated in Fig. 4.

40 The broader end of the blank, Fig. 1, being first rolled upon the mandrel to form the inner layer of the tube, and the narrower end being

wrapped about said inner layer, said outer and inner layers obviously extend unequally at the end of the finished tube, Fig. 3. The projecting wings *a* and *a'* of the broader part of the blank form inner flanges or necks over which 55 the cover or bottom may fit, and the retreated edges *c* of the blank form shoulders which meet the edges of the cover or bottom.

Similarly, a tube having one outer flange and one inner flange or neck, as seen in Fig. 4, is 60 formed by folding the blank B, Fig. 2, either end first, upon a mandrel. A tube having two outer flanges would be made by rolling the blank, Fig. 1, narrower end first upon the mandrel.

65 In tubes having only two layers, one bearing the flange or flanges and the other the retreated edge or edges, the length of the projecting part or wing which forms the flange will equal or, preferably, somewhat exceed the 70 circumference of the tube, in order that the flange may be entire in the completed tube. When the layers are more numerous, as when thin material is used, the length of the wings will vary according to the number of layers or 75 thicknesses required on the flange.

In tubes made of paper or similar material the contiguous surfaces of the layers will be glued together, as in the ordinary construction of such boxes, the glue or other cement being 80 preferably applied to appropriate parts of the blank before shaping the tube. By, also, at the same time gluing the wing which is to form the flange to receive the permanent bottom of the box, said bottom may be at once 85 applied to the tube when the latter is taken from the mandrel, and further gluing and manipulation for this purpose avoided.

If desired, the bottom may be inserted within an outer flange of the tube, and with its own 90 flange-edge outward and flush with the edge of the body. By this means a box of given capacity is materially lengthened, the bottom is elevated out of reach of injury or dampness, and the package is fitted to stand more securely upon an uneven surface.

95 I have shown only the round or cylindric form of box-body for greater convenience of illustration and description. I do not, however, wish to be limited to this form, since it 100

is plain that a square or other form of mandrel or former may be used about which to fold the sheet, to give a correspondingly-shaped body. It will also be understood that the box tube or body may be flanged either at one or at both ends, as desired.

Having thus described my invention, I claim—

1. A flanged box tube or body constructed of a single sheet folded and secured upon itself in two or more contiguous layers which extend unequally at the end of the tube, to form a

flange and shoulder adapted to receive a flanged cover or bottom flush with the surface of the tube, as described.

2. The box-tube having an outer flange at one end and an inner flange at the other, and constructed of the single sheet shown in Fig. 2, folded and cemented upon itself, as described.

FRANCIS R. DUCK.
